ATTORNEY

UNITED STATES PATENT OFFICE.

THOMAS H. REED, OF NEWARK, NEW JERSEY.

PHONOGRAPH-REPRODUCER.

1,321,476.

Specification of Letters Patent. Patented Nov. 11, 1919.

Application filed July 19, 1918. Serial No. 245,746.

To all whom it may concern:

Be it known that I, THOMAS H. REED, a citizen of the United States, residing in the city of Newark, county of Essex, and State 5 of New Jersey, have invented certain new and useful Improvements in Phonograph-Reproducers, of which the following is a full, clear, and exact description, such as will enable others skilled in the art to which 10 it pertains to make, construct, and use the same, reference being had to the accompanying drawings, and to characters of reference marked thereon, forming a part of this specification.

15 This invention relates to that class of sound reproducers which are employed in connection with disk records, one object of the invention being to facilitate and cheapen the construction of the stylus lever, and a 20 still further object being to so pivot the said stylus lever that an extremely sensitive action and freer movement of the same will be insured, thereby producing a more perfect reproducer.

25 The invention comprises a casing in which a diaphragm is mounted in the usual manner, the stylus lever being attached to the diaphragm and having one end pivotally and yieldingly mounted upon the sound box 30 casing, and means for adjusting the tension of the diaphragm; and it further comprises means for regulating the tension of the diaphragm and for balancing the reproducing lever with respect to the diaphragm and 35 casing.

Referring to the accompanying drawings, in which I have illustrated one preferable embodiment of my invention, I will proceed to describe the same, having it understood 40 that I am not limited to the specific details shown and described, as it is manifest that these may be modified without departing from the spirit or scope of the invention.

Figure 1 represents a front view of my 45 improved reproducer, constructed in accordance with my present invention.

Fig. 2 represents a side elevation of the same, and

Fig. 3 represents on an enlarged scale, a 50 fragmentary longitudinal, vertical, sectional view.

Similar characters of reference refer to like parts throughout the specification and drawings.

55 Referring to the drawings 1 represents a cylindrical casing turned inwardly at its

forward edge, to form a flange 2, and screw-threaded at its rearward edge portion for the reception of a back plate 3 which is provided with a central opening 4, and has integrally formed thereon, the usual boss 5 for attaching it to the sound conveying means which lead to the horn. The back plate 3 is screw-threaded and has screw-threaded engagement with the rear of the casing 1 for 60 supporting the plate in the casing, and for moving the plate within the casing to regulate the tension of the diaphragm, said screw threaded back plate being further provided with apertures or key-ways 6 for the 65 purpose of adjusting the same. Positioned within the said casing 1, between and bearing against the flange 2 thereof, and the inner face of the washer 7, are two annular gaskets 8 and 9 preferably made of rubber, 75 and in cross section either solid, circular and hollow, between which is supported a diaphragm 10. The diaphragm 10 is preferably made of laminated skins, or it may be made of any other suitable material employed for this purpose. Upon placing the diaphragm in position between the gaskets, the back plate 3 is screwed into the casing, 80 forcing the washer 7 toward the flange of the casing until the proper tension of the 85 diaphragm is obtained. The tension of the diaphragm may be adjusted to any degree desired by corresponding movement of the back plate 3.

Bearing centrally upon the outer face of 90 the diaphragm 10 is the inner end of the stylus lever 11, which is provided with a boss 12. On the rear side of the diaphragm is arranged a washer 13, preferably made of metal. The screw 14, which has screw 95 threaded engagement with the washer 13, passes through the boss to clamp the parts together, and to clamp the diaphragm between the boss and the washer. The stylus lever 11 is provided with an apertured extension for the reception of the ordinary 100 stylus (not shown), which is designed to be held in place by a set screw 15. The casing 1 is provided with two laterally opposed apertured ears or lugs 16 and 17, so arranged as to provide an open space therebetween, to receive a knurled adjusting nut 18, and a screw-threaded post 19, one end of 105 said post 19 being rigidly secured to the free end of the stylus lever 11, as clearly indicated in the drawings. A portion of the screw-threaded post 19, adjacent to the un-

derside of the stylus lever 11, is reduced in cross section for a portion of its length, as indicated at 20, to make the post sufficiently flexible, to serve not only to hold the lever upon its bearing, but also as a spring to exert an influence upon the oscillation of the lever.

The free end of the screw-threaded post 19 which projects beyond the apertured ear 10 or lug 17 is engaged by a lock nut 21, which bears upon the underside of the apertured ear or lug 17 to lock the threaded post 19 and stylus lever in their adjusted positions.

In the operation of the invention, after the parts are assembled as shown in Figs. 2 and 3 of the drawings, the nut 21 serves to lock the parts in their adjusted position.

In order to provide a sufficient amount of tension upon the screw-threaded post 19 for effecting a proper regulation of the stylus lever to produce the best results it only becomes necessary to release the locking nut 21 and then by turning the knurled adjusting nut 18 in either direction, will cause the stylus lever to be drawn toward or away from the casing 1, and a proper tension of the diaphragm can be effected. By turning the lock nut 21 back upon the underside of the apertured ear or lug 17 the parts are positively locked in their adjusted position, against accidental displacement. The back plate 3, therefore not only serves to tension the diaphragm but it also serves to place the stylus lever under greater or less tension corresponding to the tension of the diaphragm.

My improved construction enables me to dispense with a number of parts, thereby reducing the actual number of parts, to obtain the following results, to a minimum, namely; a very sensitive so-called micrometer adjustment of the stylus lever and diaphragm, a more perfect reproduction, and a clearer tone as well as a freer movement of the stylus lever.

Experience has demonstrated that the organization above described is a highly efficient one, and while I have shown the preferred embodiment of my present invention I do not wish to be limited to the exact details of construction shown and described, as obvious modifications thereof, not involving the exercise of invention, may be made by any skilled mechanic, and such de-

partures from what is herein set forth, I consider within the scope and terms of my claims.

Having thus described my invention, what I desire to secure by Letters Patent, is:—

1. A reproducer comprising a hollow casting provided with opposed apertured lugs, a diaphragm, a stylus lever secured to the center of the diaphragm, a screw-threaded post rigidly secured to the stylus lever, said post extending from the underside of the stylus lever, and at right angles thereto, and through said apertured lugs, an adjusting nut located between said apertured lugs and mounted upon and having screw-threaded engagement with said screw-threaded post for effecting a proper regulation of said stylus lever.

2. A reproducer comprising a hollow casting provided with opposed apertured lugs, a diaphragm, a stylus lever secured to the center of the diaphragm, a screw-threaded post rigidly secured to the stylus lever, said post extending from the underside of the said stylus lever, and at right angles thereto, and through said apertured lugs, said screw-threaded post adjacent to the underside of the stylus lever being reduced in cross section for a portion of its length, an adjusting nut located between said apertured lugs and mounted upon and having screw-threaded engagement with said screw-threaded post for effecting a proper regulation of said stylus lever.

3. A reproducer comprising a hollow casting provided with opposed apertured lugs, a diaphragm, a stylus lever secured to the center of the diaphragm, a screw-threaded post provided with a flexible portion rigidly secured to the outer free end of the stylus lever and extending through said apertured lugs designed to solely support the stylus lever free from the casing, and an adjusting nut located between said apertured lugs and mounted upon and having screw-threaded engagement with said screw-threaded post for effecting a proper regulation of said stylus lever.

This specification signed and witnessed this 21st day of June, 1918.

THOMAS H. REED.
